PRESSING MACHINE

Albert U. Walter, Baltimore, Md.

Application April 19, 1938, Serial No. 202,939

19 Claims. (Cl. 38—28)

This invention pertains to garment presses, and more particularly to that type wherein the pressing operation is effected through the utilization of power driven mechanism, as for instance a constantly rotating electric motor.

In the structure herein shown and described, various operations necessary to a complete treatment of a garment may be effected through the utilization of power mechanism; first, the head may be caused to move down into light contact with the garment imposed upon the buck; secondly, the head may be caused to move into light pressing relation with the garment imposed upon the buck, and thereafter, as a continuing operation, caused to move into heavy pressure relation with the buck and to be automatically locked in such position; and, lastly, the head may be oscillated toward and from the buck to effect what is known in the trade as a "patting operation" with reference to the garment which is at that time resting upon the buck. The sequence of these operations may be varied as desired.

With these and other advantages in view, as will hereinafter appear, reference is had to the annexed drawings, wherein:

Figure 1 is a side elevation, with parts broken away and with the pressing elements in their heavy pressing relation;

Fig. 2, a rear elevation of the lower portion of the closing and opening toggle and certain of the actuating mechanism cooperative therewith;

Fig. 3, an elevation of the operative mechanism with the parts in that position where the press head will be elevated and susceptible of going through a cycle to effect the patting operation;

Fig. 4, a vertical sectional view taken on the line IV—IV of Fig. 3;

Fig. 5, a detail sectional view showing the mounting of one end of the clutch band;

Fig. 6, a side elevation of the hand operated mechanism utilized for initiating the heavy pressure, the full line position showing the parts interlocked to preclude movement thereof;

Fig. 7, a front elevation of the parts shown in Fig. 6;

Fig. 8, a perspective view of a fixed supporting bracket which carries the cam element utilized for initiating the clutching operation and certain limiting stop elements;

Fig. 9, a perspective view of certain parts of the clutching mechanism, including the clutch band and certain associated parts;

Fig. 10, a view of the toggle mechanism and the straightening and releasing means; and

Fig. 11, a side elevation of a slight modification of the press closing and press opening mechanism.

Broadly stated, the structure involves a fixed buck or pressing element, a head carried by a lever, a toggle for raising and lowering said lever, a constantly rotating motor, means under the direct control of the operator for establishing a connection between said motor and the toggle to partially straighten the same to bring about a patting operation between the head and buck, and other means likewise under the control of the operator for fully straightening the toggle and maintaining it as long as desired in such straightened position, and this without stopping the motor.

The means for straightening the toggle, namely a constantly reciprocating rod or bar, also functions to break the toggle when the parts are moved to press releasing position.

In the drawings, 10 denotes the base of the machine from which arise the side frames or plates 11 and 12. Above the base is the usual buck 13 cooperative to effect a pressing relation with a head 14 carried at the forward end of a lever 15. The lever 15, as is usual, is fulcrumed at 16 upon the upwardly extending portions 17 of the machine frame.

The rear end of the lever 15 will preferably be counterweighted and it is designed to be raised and lowered through the straightening and breaking of a toggle comprising links 18 and 19 pivotally connected as at 21. The lower link 18 is pivoted to the base of the frame at 22 and the upper end of the link 19 is pivotally connected at 23 to a bell crank lever 24, which, in turn, is pivotally connected to the head carrying lever 15 as at 25.

To the upwardly extending arm of the bell crank 24 there is attached a box 26 in which is housed a spring 27 co-operative with a head or abutment 28 upon the forwardly extending rod 29 which passes through a fixed cross-bar 31 attached to and located between the side members of the head carrying lever 15. A hand wheel 32 is secured to the forward end of the rod 29 and by turning it the spring 27 may be placed under greater or less compression and thereby shorten the effective length of the rod and, consequently, the effective pressure which may be brought about between the elements 13 and 14.

As above indicated, the mechanism is designed to be driven by a constantly rotating electric motor EM which, however, has attached to its shaft a worm 33 (see Fig. 4) meshing with the worm wheel 34 keyed to a shaft 35 mounted in

- suitable bearings located within the housing 38 secured to the frame element 11. The shaft 35 extends inwardly as shown in said figure, and has keyed to it a drum-like member 37 the outer face whereof forms a gripping surface for a clutch band hereinafter described. The motor EM produces a consant rotating movement of the other driving members, 33, 34, 35 and 37, while the machine is operated.
- Extending outwardly from the inner face of the drum-like member 37 is an eccentrically positioned crank pin or stud 38, said pin being provided with a suitable bushing or bearing over which is passed the eye of a push bar 39. It is held in place upon the stud by any suitable means.
- The drum-like member 37 is recessed or has an annular groove formed in its inner face, producing an annular bearing, said groove and bearing both being concentric with the shaft 35. A bushing is mounted upon the bearing face and forms the support for a hub 42 of a casting denoted generally by 43 (see more particularly Fig. 9), herein termed a clutch band carrier.
- The member 43 is provided with a laterally extending bracket 44 in which is adjustably mounted a spring box or housing 45 (see Fig. 5) and cooperating with the spring in said housing and slideable relative to the housing is a threaded bolt 46 attached to one end of a clutch band 47. The opposite end of the band is attached to a pin or stud 48 which is formed eccentrically as an integral part of a rocking stub shaft 49. The shaft 49 is mounted in a laterally extending sleeve 51 formed as an integral part of the member 43 and has pinned to its outer end an arm 52 (see Fig. 9). Arm 52 is provided with a laterally extending finger 53 which forms the anchorage for one end of a coil spring 54, the opposite end of which underlies a finger or projection formed as an integral part of said member 43. In addition to the finger 53, the arm 52 has mounted thereon a roller 55 which tends to rotate the shaft 49 clockwise and place the spring under compression when the arm is moved by a cam now to be described.
- The cam is best shown in Fig. 8. The active face of the cam is denoted by 56 and is concentric with the shaft 35 and the parts allied therewith when said cam is in its operative or its outward position. The cam is pivotally mounted upon a stud 57 secured to a casting or bracket-like member 58 rigidly affixed to the frame element 12 by a bolt 59, and to both side frame members 11 and 12 by a through bolt 61. The cam is interrupted or has a depression formed therein adjacent its pivot support 57, so that the roller 55 when it travels into line with said depression may move inwardly thereof under the impulse of the spring 54.
- Cam 56 also has an arm 62, the outer end whereof is bifurcated and in which there is rotatably mounted a through pin 63, through which extends a draw link 64 carrying a nut 60 at its upper end. The link 64 is encircled by a spring 65 which reacts between the bifurcated end of arm 62 and lock nuts 66 threaded upon the link. At its lower end, the link is connected to a foot lever 67 fulcrumed at 68 in the machine frame. Spring 65 coacts with the link 64 to form a resilient thrust connection between the foot lever 67 and the cam arm 62 for the purpose of absorbing any excess motion during operation of the parts. The foot lever is provided with an adjustable stop 70 to limit the downward move-

ment of its inner end. Lever 67, of course, extends outwardly to a point where it may be operated or depressed by the operator's foot.

Cam 56 is provided with an integrally formed step element 69 which cooperates with a similar fixed stop 71 upon the bracket 58 to limit the outward movement of said cam. In said outward position the cam exerts its maximum contraction of the clutch band 47. Wear and proper tension of the band is taken care of by axial adjustment of the spring box 45. Bracket 58 at its lower end is provided with a laterally extending arm 72 and a tension spring 73 is secured between the outer end of said arm 72 and a finger 74 formed upon the cam element. The spring normally holds the parts in inoperative position.

Extending downwardly from the upper portion of the bracket 58 is a fixed arm 75 having formed at its lower end a stop 76 designed to cooperate with a similar stop 77 carried by the member 43 when the parts come to the position shown in Fig. 1, that is to stay, when the head and buck are brought together in heavy pressing relationship. In other words, the stop 77 which is movable with the member 43 comes into contact with the fixed stop 76 carried by the bracket element 58 and arrests the rotative movement of the member 43, thereby limiting the movement of the toggle elements 18 and 19 in locked position, which position is on or slightly past dead-center, as in Fig. 1.

Hooked to the bolt 61 is the lower end of a heavy coil spring 78. The upper end of this spring, in turn, is connected to the forward extension of the bell crank 24, as best shown in Fig. 1. Spring 78 serves in a measure to swing the rear end of the head carrying lever 15 downwardly to open the press. In addition to the spring 78, I propose to employ a second spring 79 adjustably secured at its forward end to a fixed portion of the frame and at its rear or inner end to the lower link or member 18 of the toggle mechanism.

The push bar 39, heretofore referred to, is designed to move the toggles to heavy pressure position (as shown in Figs. 1 and 10), as well as to break the same, and a pitman 81 is employed to partially straighten the toggle and thus bring the head and buck together to secure a light pressure or to reciprocate the head to and away from the buck, to secure the patting action.

Pitman 81 at its rear end is pivotally connected as at 82 to the lower link 18, and at its forward end is pivotally attached to a stud or bearing member 83 carried by the member 43 (see Fig. 9). The pitman 81 at no time fully closes the press, or in other words, does not fully straighten the toggle as will hereinafter more fully appear, but can only bring it to the position shown in dotted lines in Fig. 3. The contacting of the head and buck determines this position. In this position, a light pressure is obtained between the head and the buck, which pressure may be varied slightly by the clutch adjustment. The clutch 65 acting through the pitman 81 cannot straighten the toggle since slightly past this point the clutch will be released because the roller 55 will drop into the depression in the cam adjacent to its pivot support 57, above referred to, thereby releasing 70 the clutch.

The upper portion of the link 18 of the toggle mechanism is bifurcated and the push bar 39 extends freely therethrough. Adjacent its rear end and on its under face, it is provided with a

shoulder 84 designed under certain conditions, hereinafter set forth, to contact a roller 85 mounted upon a shaft or bolt carried by the bifurcated portion of the link 18. Adjacent the rear end 5 and to each side thereof, the push bar 39 is provided with lugs 86 (see more particularly Figs. 1 and 2) which project outwardly to such an extent that under certain conditions they will contact pads 87 formed upon the rear face of the 10 upper portion of the link 18 and break the toggle.

Pivottally connected to the rear end of the push bar 39 is a depending link 88, the lower portion of which is slotted at 89 and through 15 which slot passes a pin 91. The pin 91 is secured in the bifurcated rear end of the lever 92 fulcrumed upon a pin 93 supported in a fixed portion of the frame. The inner end of the lever 92 is weighted as at 94 so that normally it will 20 occupy the position shown in Fig. 3.

Again referring to Figs. 1 and 3, it will be seen that the lower link 18 is provided with a laterally extending arcuate-shaped ledge or projection 95 which is concentric with the pivotal 25 point 22 of the link. The under face of the lever 92 is formed with a shouldered portion 96 which when the press is opened, overlies the lateral projection 95 and prevents the lever from being rocked clockwise. When, however, the toggle 30 mechanism is moved from the full line position to the dotted line position shown in Fig. 3, or is partially straightened, the shouldered portion or projection 96 will clear the laterally projecting ledge 95 and allow the lever 92 to move clockwise 35 under a pull exerted by the operator, as will shortly be described, allowing the pin 91 to travel downwardly and as a consequence allow the link 88 to move downwardly so that the push bar 39 may drop down to a position where the shoulder 40 or abutment 84 will contact the roller 85 and fully straighten the toggle as the push bar is moved to its extreme rear position, thereby effecting heavy pressure.

Should the press seek to open under abnormal 45 operation, or when it is not mechanically released by the operator, the member 95 coacting with the shoulder 96 will prevent the toggle from moving beyond the toggle position as shown in dotted lines in Fig. 3, or, in other words, will 50 prevent the press from flying open, with a possibility of injuring the operator. The ledge 95 and the shouldered portion of the lever 92 thus perform a dual function, as above set forth.

As originally noted, the motor is constantly 55 driven over a succession of cycles of pressing operations but is not in effective driving relation with certain of the parts until the operator desires either to bring the head and buck into light contact or to effect patting, or to apply 60 heavy pressure.

To effect the patting operation, the operator merely depresses the outer end of the lever 67 which rocks the arm 62 and throws the cam 56 outwardly. The roller 55 and arm 52 are 65 thereby rotated in a clockwise direction, which motion through the eccentric stud 48 effects contraction of the clutch band 47, and through the linkage brings the head and buck together. The operator then releases the lever and as soon as 70 the head rises a slight amount, depresses it again. In this manner, the operator causes the head to oscillate to and from the buck, in other words secures a patting action.

To effect heavy pressing operation, it is necessary to bring the push bar 39 into the position 75

shown in Fig. 1, where the shoulder 84 thereof will contact the roller 85 and move the parts from the dotted line position of Fig. 3 to that of Fig. 1. This dropping down of the rear end 5 of the push bar 39 is effected through the following mechanism:

Pivottally connected to the lever 92 is a link 97 which extends upwardly and is, in turn, pivottally connected to a bell crank 98 pivoted at 99 upon the fixed portion of the machine frame. 10 A link 101 extends forwardly from the uppermost end of the bell crank 98 and, in turn, is connected to the lower end of a downwardly extending arm 102 fulcrumed at its upper rearwardly extending end on a through pin 103. Said 15 pin is mounted in the upper end of a bracket or standard 104, the upper portion whereof is yoke-shaped, forming a pair of upwardly extending arms 105 and 106.

Also fulcrumed upon the through pin 103 is a 20 hand lever 107 provided with a laterally extending lug 110 which underlies a lug 110a formed upon the arm 102. By reference to Figs. 1 and 6, it will be clear that if the hand lever 107 be raised, the lug 110 will coact with the lug 110a 25 to swing arm 102 in a clockwise direction, thus drawing the link 101 to the left. Bell crank 98 will thereby be rocked in a counterclockwise direction to exert an upward pull upon the link 97 and raise the forward end of the weighted lever 92. As a consequence, the rear end of lever 92 will be moved downward which permits the push bar 39 to swing down to the full line position of Figs. 1 and 10 where it may engage the roller 85 and fully straighten the toggle. If at 30 the time the rear end of the lever 92 is moved downward, the shoulder 84 is to the right of roller 85, the push bar cannot drop into operative position. However, the rear end of the lever 92 is permitted to drop to its operative position 35 because of the slot in the link 88. The push bar 39 will not drop into operative position until it moves to the left sufficiently to bring the shoulder 84 to the left of the roller 85.

Hand lever 107 is provided with a second laterally extending lug 108 adapted to coact with a lug 109 formed on the forward short end of a lever 111 also fulcrumed upon the pin 103, the lever 111 at its rear end having adjustably attached thereto a tension spring 112 which normally rocks said lever in a clockwise direction. The lever overlies the plunger or stem 113 of a head steaming valve denoted generally by 114 which, when the lever is caused to move counterclockwise by depression of the hand lever 107 40 45 50 55 allows the plunger to rise and the valve to open.

Normally, lever 107 is locked against upward movement and it is necessary for the operator to use both of his hands to effect its release and move it. To that end the following mechanism 60 is employed: Lever 102 above its pivotal connection with the draw link 101 is provided with an inward laterally extending lug 115 which normally stands in alignment with a lug 116 extending outwardly from a second hand lever 65 117 fulcrumed at 118 upon the member 104. A spring 119 having its upper end seated in a socketed element 121 formed as an integral part of the lower portion of the lever 117 and contacting at its lower end with the member 104 tends to 70 move the lever 117 upwardly into the full line position (see Fig. 6). When thus positioned, the lugs 115 and 116 are in interfering relation so that the lever 107 cannot be moved upwardly and as a consequence, the lever 92 cannot be 75

5 moved clockwise. It is necessary, therefore, for the operator to first move the lever 117 downwardly to withdraw the lug 116 outwardly so that the lever 107 with its lug may be swung upwardly. This mechanism, in effect, is an interlock which necessitates the operator's using both hands to position the parts properly.

10 The push bar 39 cannot be lowered to effect heavy pressure until the head is approximately in contact with the buck because the roller 85 would be to the left of the shoulder 84, even when the push bar is in its extreme forward position. Therefore, when it is desired to effect heavy pressure, it becomes necessary to first 15 lower the head until it contacts the buck by operating the clutch, and to then lower the free end of the push bar 39 and this is done by manipulating the levers 107 and 117 as above described, which has the effect of rocking the lever 92 clockwise. This permits the pin 91 to move 20 down in the slot 89 and allows the rear end of the bar 39 to come to its lower position where the shoulder 84 will be in alignment with the roller 85 and upon the next rearward movement 25 of the bar 39, pressure will be exerted upon the toggle mechanism to carry it to fully straightened heavy pressure applying position.

30 It is to be noted that immediately after the push bar commences to straighten the toggle that the roller 55 drops into the depression in the cam, thereby releasing the clutch. In other words, even though the operator holds the lever 67 depressed, the clutch becomes inoperative immediately after the beginning of the cycle of 35 operation which applies heavy pressure and remains inoperative therethrough, and as long as heavy pressure is applied. It should also be noted that the lever 92 cannot be rocked clockwise into operative position until the head and 40 buck are in contact in which position the left edge of the ledge 95 is to the right of the shoulder 96, (see the dotted line position of Fig. 3). The arrangements just described provide a dual safety factor.

45 The parts are so proportioned that the continued reciprocation of the push bar 39 merely carries the shoulder away from the straightened toggle, and consequently the roller 85 on its forward stroke, and then on its rearward stroke to a 50 point where it barely contacts the roller 85, or slightly short thereof, as the toggle may be carried slightly past dead-center.

55 When the parts are in heavy pressure position, the lug 115 overlies the lug 116 and the parts are held in that position through the action of the spring 119. To release the press from heavy pressure, the lever 117 is depressed, withdrawing the interengagement of the lugs just referred to and permitting the parts through 60 the action of the weight 94 and a spring 122 connected with the bell crank 98 and a fixed member of the press frame, to swing lever 92 about its pivot in a counterclockwise direction. Since the pin 91 is at the upper end of the slot 89, this movement of the lever 92 raises the push bar 39 from the full line position of Fig. 1 to that of Fig. 3.

70 Upon movement of the push bar 39 to the left (Figs. 1 and 3), the wings 86 will contact the pads 87 and exert sufficient pull upon the toggle to break the same. When the press is locked in heavy pressure relation, the link 39 reciprocates in a line between its pivotal connection and the roller 85 at substantially right angles to a

line passing through the toggle pivots (see Fig. 10).

When, however, the push bar 39 is being raised toward the dotted line position in Fig. 10, swinging about its fulcrum, the wings 86 more closely approach the pads 87, and when fully raised and the push bar 39 drawn to the left to its full extent, it will exert a pull as well as sufficient movement upon the toggle to break the same. The press will then open completely under the action of the springs and counterweight heretofore described.

10 In Fig. 11 a slight modification of the mechanism is shown, which will now be described. In the construction heretofore set forth, the pedal 15 was used solely to actuate the clutch, whereas in the modification about to be described the pedal is used only for releasing the press from locked position. Mounted on the head is a bell crank handle 123 and its upwardly extending 20 arm is attached to a link 124 which, in turn, is connected to a bell crank 125 pivoted at 126 to a fixed portion of the frame. Connected also to the rearwardly extending arm of the bell crank 125 is a link 127 and a spring 128, the other 25 end of said spring being attached to a fixed portion of the frame. The spring tends to draw the rear end of the lever downwardly and to raise the bell crank handle 123. Link 127 at its lower end is attached to the arm 62 of the corresponding mechanism heretofore described.

30 In addition to the lever 123, there is mounted on the head a second bell crank handle 107^a having a downwardly extending arm 140 formed integrally therewith. Pivotedly connected to the 35 lower end of said arm is a rod 141 the rear end whereof is attached to the upwardly extending member of the bell crank 142 fulcrumed upon the pin 126 or a similar fixed point upon the frame. The rearwardly extending arm of said 40 bell crank 142 has connected to it a link 143 which at its lower end is pivotally attached to the weighted lever 92, said lever being the same as that described in connection with the first depicted mechanism insofar as its operation with 45 the push bar and its associated elements is concerned.

Rigidly secured to the bracket 44 of the clutch band carrier 43 is a plate 129 designed to cooperate with the upper end of a foot lever 131 50 fulcrumed at 132 upon the frame, the lever extending forwardly of the press frame where it may be actuated by the operator's foot. Attached to the upwardly extending arm of the lever 131 is a link 133 which, in turn, is pivotally connected to a locking pawl 134 fulcrumed at 135 upon a fixed portion of the frame. Spring 136 is attached to the lever 134 and tends to move it in a clockwise direction to bring its upper end into cooperative relation with a lug 60 137 mounted upon the weighted end of the lever 92, corresponding to the lever heretofore described and so lettered.

65 The operation with this modified form of structure is as follows: By depressing the bell crank handle 123 the clutch is actuated, which moves the head in contact with the buck. At this point, if it is desired to lock the press, the handle 107^a is moved upwardly. This, in turn, moves the lever 92 to the position shown in Fig. 11. The 70 pawl 134 then, by means of the spring 136, is moved beneath the lug 137 and maintains the lever 92 in its operative position. In this position, as with the first described construction, heavy pressure and locked condition is obtained 75

between the head and the buck. Once the pawl 134 engages the lug 137 the operator may remove his hands from the handle 123 and the lever 107^a, even though the push bar 39 has not functioned to lock the press. In order to unlock the press, the pedal lever 131 is depressed, the first movement of which releases the pawl and permits the lever 92 to move counterclockwise to its inoperative position. A further movement of the pedal lever 131 causes a pressure between its upwardly extending arm and the plate 129, which action rotates the clutch band carrier 43 in a clockwise direction. This exerts a pull to the left on the pitman 81 and thereby breaks the toggle and opens the press.

In the modified construction, as in the construction described above, it is necessary to have the head and buck in contact before heavy pressure can be applied. In order to lock the press, it is necessary for the operator to hold the head and buck in contact by pressure upon the bell crank handle 123 with one hand and with the other to then push the lever 107^a upwardly. In other words, it is necessary for the operator to use both hands to lock the press, and as this is necessary, there is no possibility of an operator's hand being crushed between the head and buck.

Since the pedal lever 131 mechanically releases the press from the locked position, it is no longer necessary to use the lugs 86 and pads 87, previously described, which, therefore, may be eliminated. The foot release mechanism as above set forth gives a much more rapid release of the press as compared to the mechanism first described, wherein the push bar 39 must come to a predetermined position in its cycle of movement before press release may be had.

It will further be appreciated that in both forms the press head may be drawn down by hand to meet the buck.

With the construction first described, the press is opened through power actuation, whereas in the modified form the opening is dependent upon power applied by the operator.

45 What is claimed is:

1. In a garment pressing machine, the combination of cooperative pressing elements, one of which is movable toward and from the other; a toggle interposed between the movable element and a fixed portion of the machine, the parts being so proportioned that when the toggle is in substantially straight position it exerts heavy pressure between the pressing elements; a rotatable driving member and means for maintaining the same in constant rotation over a succession of cycles of pressing operations; a pitman connected to the toggle; means under the control of the operator for effecting a driving connection between the rotatable driving member and the pitman to move the latter short of straight position of the toggle; a push bar for straightening said toggle, means actuated by said rotatable driving member for constantly reciprocating said bar; and means likewise under the control of the operator for shifting said bar into cooperative relation with the toggle to straighten the same.

2. In a garment pressing machine, the combination of a fixed pressing element; a movable pressing element; toggle mechanism for moving the latter into pressing position; a constantly rotating member; a bar extending from said member toward and past one of the links of the toggle; an abutment carried by the toggle and designed to cooperate with a shoulder formed upon the rear portion of the bar; a laterally extending

wing at the rear portion of the bar adapted when the bar is drawn forward to contact the toggle and to move the same from its straightened position; a link extending from the bar, said bar and link being pivotally attached to each other; a lever fulcrumed upon the fixed portion of the frame; a connection between the rear end of said lever and the link, means effective upon the lever to normally throw its rear end upwardly to raise the link and consequently to elevate the rear end 10 of the bar and to thereby maintain said bar out of range of the abutment on the toggle; and means under the control of the operator for causing the link and bar to move downwardly and the abutment on the bar to be brought into alignment with the abutment on the toggle to effect straightening of the toggle to bring about heavy pressure between the pressing elements.

3. In a garment pressing machine, the combination of a fixed pressing member; a movable pressing member; a head carrying lever fulcrumed upon a fixed portion of the machine to which the movable pressing member is attached; a toggle comprising two links pivotally connected to each other and to the lever and a fixed portion 25 of the frame, respectively; an arcuate-shaped ledge or projection extending laterally from the lowermost link; a control lever fulcrumed upon a fixed portion of the frame at a level above said ledge, said lever having a shoulder formed upon 30 its under face and likewise being counterweighted at its forward end with its rearward end overlying the ledge aforesaid, and a detent for holding said lever in position with its shoulder depressed into the path of said ledge; means for 35 moving the toggle toward partially straightened position to effect a patting operation of the machine; a constantly reciprocating bar, the rear end of said bar being in juxtaposition with the lower link of the toggle and having a shoulder 40 formed thereon; an abutment carried by the lower link of the toggle; a link depending from the rear end of said reciprocating link; a pin and slot connection between the lower end of said last-named link and the rear end of the control 45 lever, the pin normally standing at the upper end of the slot and consequently holding the rear end of the reciprocating bar in an elevated position with its shoulder out of alignment with the abutment; and means under the control of the operator 50 for raising the counterweighted end of the control lever, thereby permitting the depending link to move downwardly and the reciprocating bar to likewise move downwardly and to bring its shoulder into alignment with the abutment upon 55 the lower link of the toggle; and means for releasing said detent and also effective for moving the toggle toward collapsed position.

4. In a garment press machine, the combination of a buck; a head mounted for movement toward and from the same; a rotatable driving member and means for maintaining the same in constant rotation over a succession of cycles of pressing operations; toggle means interposed between a fixed portion of the machine and the head for moving the latter and movable between a collapsed position and a straightened position; means interposed between said toggle and the rotatable driving member for initially moving the toggle from its fully collapsed position toward 70 straightened position; and other means constantly actuated by the rotatable driving member and effective for engaging the toggle in an initially moved position and moving the same toward its straightened position and thereby 75

moving the head into heavy pressing relation with the buck.

5. In a garment press machine, the combination of a buck; a head mounted for movement toward and from the same; a rotatable driving member and means for maintaining the same in constant rotation over a succession of cycles of pressing operations; toggle means interposed between a fixed portion of the machine and the 10 head for moving the latter and movable between a collapsed position and a straightened position; means for initially moving the toggle from its fully collapsed position into an initially moved position, and including an actuating member 15 capable of movement by said rotatable driving member through a predetermined distance and means for connecting said actuating member to said rotatable driving member; and other means constantly actuated by the rotatable driving member and effective for engaging the toggle in the initially moved position and moving the same toward its straightened position and thereby to move the head into heavy pressing relation with the buck.
- 20 6. In a garment press machine, the combination of a buck; a head mounted for movement toward and from the same; a rotatable driving member and means for maintaining the same in constant rotation over a succession of cycles of 25 pressing operations; toggle means interposed between a fixed portion of the machine and the head for moving the latter and movable between a collapsed position and a straightened position; means for initially moving the toggle from its 30 fully collapsed position into an initially moved position, and including an actuating member capable of movement by said rotatable driving member through a predetermined distance and manually controllable means for connecting said 35 actuating member to said rotatable driving member; and other means constantly actuated by the rotatable driving member and effective for engaging the toggle in the initially moved position and moving the same toward its straightened 40 position and thereby to move the head into heavy pressing relation with the buck.

7. In a garment pressing machine, the combination of cooperative pressing elements, one of which is movable toward and from the other; a 45 toggle interposed between the movable member and a fixed portion of the machine; a constantly rotating driving member having a crank pin; a push bar attached to said crank pin and reciprocated thereby; a clutch having two clutch parts, 50 one of which parts is driven with said driving member; a pitman attached to the other said clutch part and pivotally connected at its opposite end to one of the links of the toggle; means under control of the operator for engaging the 55 clutch parts together; an abutment carried by the toggle; a shoulder formed upon the push bar cooperative with said abutment to straighten the toggle; and means for shifting the push bar into and out of active relation with the abutment.

- 60 8. In a garment pressing machine, the combination of cooperative pressing elements, one of which is movable toward and from the other; a toggle interposed between the movable member and a fixed portion of the machine; a constantly 65 rotating driving member having a crank pin; a push bar attached to said crank pin and reciprocated thereby; a clutch having two clutch parts, one of which parts is driven with said driving member; a pitman attached to the other said clutch part and pivotally connected at its 70 opposite

site end to one of the links of the toggle; clutch control means including a device under control of the operator for engaging the clutch parts together and also including means for effecting release of the clutch at a point in the movement 5 of the pitman just short of the straightening of the toggle; an abutment carried by the toggle; a shoulder formed upon the push bar cooperative with said abutment to straighten the toggle; and means for shifting the push bar into and out of 10 active relation with the abutment.

9. A structure as set out in claim 8, wherein the means for releasing the clutch comprises a cam member and a roller member cooperative with the cam member, said roller member being 15 mounted to move with said other clutch part and said cam member being mounted on a fixed portion of the machine, said cam member being so contoured as to release the clutch when the toggle reaches a position close to but short of 20 straightened position, and spring means for causing said cam and roller members to bear against one another.

10. In a garment pressing machine, the combination of a buck; a head mounted for movement 25 toward and from the same; a constantly rotating driving member; toggle means interposed between the fixed portion of the machine and the head for moving the latter and movable between a collapsible position and a straightened position; and two separate driving connections between the driving member and the toggle means, one of said driving connections including elements for initially moving the toggle from its 30 collapsed position toward the straightened position and terminating said initial movement prior to completed straightening of the toggle, the other said driving connection being incapable of moving the toggle from its collapsed position, and effective for engaging the toggle in its initially 35 moved position and straightening the same whereby to effect heavy pressure between the buck and the head.

11. In a garment pressing machine, the combination of cooperative pressing elements, one of 45 which is movable toward and from the other; toggle means to move the movable element toward the other element and including a pair of toggle links movable between a collapsed position and a straightened position; first means for 50 moving the toggle links from a collapsed position toward an intermediate position for applying a light pressure between said pressing elements; a reciprocable element cooperating with a toggle link to move the said links from the intermediate 55 position into the straightened position and thereby effect heavy pressure between the pressing elements, said machine also including means for preventing cooperative engagement of the said reciprocable element with the said toggle link in 60 the collapsed position of the toggle; and constantly rotating means for reciprocating said reciprocable element continuously over a succession of 65 cycles of pressing operations.

12. A pressing machine as set forth in claim 11, 65 and including means for changing the path of movement of the reciprocable element to render it effective to break the toggle and move the movable element from the position at which heavy pressure is exerted between the pressing 70 elements.

13. A pressing machine as set forth in claim 11, 75 wherein the constantly reciprocated element comprises a bar having a shoulder presented adjacent the toggle, and wherein the toggle is pro-

vided with a roller against which the shoulder abuts in the toggle-straightening relation of the parts.

14. A pressing machine as set forth in claim 11, wherein the constantly reciprocating element comprises a bar provided with a shoulder, an abutment on one of the toggle elements cooperative with said shoulder in the toggle-straightening relation of the parts, and means for shifting the bar into a position in which it reciprocates with the shoulder moving in a path out of contact with said abutment, the bar being also provided with at least one lateral extension adapted to co-act with the toggle for breaking the same when the bar is in the said position.

15. In a garment press machine, the combination of a buck; a head mounted for movement toward and from the same; a constantly rotating driving member; toggle means interposed between a fixed portion of the machine and the head for moving the latter and movable between a collapsed position and a straightened position; means interposed between said toggle and the driving member for initially moving the toggle from its fully collapsed position toward straightened position; and other means constantly actuated by the driving member and effective for engaging the toggle in an initially moved position and moving the same toward its straightened position and thereby moving the head into heavy pressing relation with the buck, said other means including a bar connected with the driving member for constant reciprocation thereby, said bar including means engageable with a toggle link after said link has been brought into the initially-moved position and being effective for straightening the toggle from said initially-moved position.

16. In a garment press machine, the combination of a buck; a head mounted for movement toward and from the same; a constantly rotating driving member; toggle means interposed between a fixed portion of the machine and the head for moving the latter and movable between a collapsed position and a straightened position; means interposed between said toggle and the driving member for initially moving the toggle from its fully collapsed position toward straightened position; said interposed means including a clutch and a pitman, said clutch being under the control of the operator and being effective when engaged to cause the driving member to move the pitman and therewith the toggle into an initial partially straightened position; and other means constantly actuated by the driving member and effective for engaging the toggle in an initially moved position and moving the same toward its straightened position and thereby moving the head into heavy pressing relation with the buck, said other means including a bar connected with the driving member for constant reciprocation thereby, said bar including means engageable with a toggle link after said link has been brought into the initially-moved position and being effective for straightening the toggle from said initially-moved position.

17. In a garment pressing machine, the combination of a buck; a head carrying lever; a head mounted thereon; a toggle mechanism for moving said lever; a constantly reciprocating bar engageable during its stroke with the toggle to move the same to straightened position for applying pressure between said buck and head; and means for shifting said bar under control of the operator for presenting it in a position in which it engages with the toggle mechanism during its reciprocation and moves the toggle mechanism to straighten the toggle, and in which said bar in another position is out of effective engagement with the toggle mechanism.

18. In a garment pressing machine, the combination of a buck; a head carrying lever; a head mounted thereon; toggle mechanism for moving said lever; a constantly reciprocating bar engageable during its stroke with the toggle to move the same to straightened position for applying heavy pressure between said buck and head; means for shifting said bar under control of the operator for presenting it in a position in which it engages with the toggle mechanism during its reciprocation and moves the toggle mechanism to straighten the toggle, and in which said bar in another position is out of effective engagement with the toggle mechanism; and means independent of the reciprocating bar for partially straightening the toggle to an intermediate position of light pressure, a detent for preventing the return of the toggle from said intermediate position, and manually controlled means for releasing said detent.

19. In a garment pressing machine, the combination of a buck; a head mounted for movement toward and from the same; a constantly rotating driving member; toggle means interposed between a fixed portion of the machine and the head for moving the latter and movable between a collapsed position and a straightened position; means interposed between said toggle and the driving member for initially moving the toggle from its fully collapsed into an intermediate position, and including a rockable member and manually-controllable means for effecting actuation of said rockable member from said driving member; and separate means including a part constantly moved by said driving member and when in one position being effective to engage the toggle means to move the same from the intermediate position into the straightened position and when in another position being ineffective to move or control the toggle; means for shifting the said part from one said position to the other, a detent for preventing the return of the said part from said engaging position; and means for effecting the rapid opening of the press and including a device for releasing the detent and a device effective upon release of the detent for acting upon the toggle to effect a collapse thereof.

ALBERT U. WALTER.
